SARI-TYPE DRESS

Janice C. Moran, San Bernardino, Calif.

Application November 13, 1956, Serial No. 43,734

Term of patent 14 years

(Cl. D3—26)

I claim:

The ornamental design for a sari-type dress, substantially as shown.
